The ornamental design for a spring clamp jaw assembly, as shown and described.

DESCRIPTION

FIG. 1 is a perspective view of a spring clamp jaw assembly, with an associated spring clamp shown in dashed lines; FIG. 2 is a right side elevation view thereof, with an associated spring clamp shown in dashed lines, wherein the left side elevation view is a mirror image of the right side elevation view;

FIG. 3 is a top plan view thereof, with an associated spring clamp shown in dashed lines, wherein the bottom plan view is a mirror image of the top plan view;

FIG. 4 is a front elevation view thereof, with an associated spring clamp shown in dashed lines;

FIG. 5 is a rear elevation view thereof, with an associated spring clamp shown in dashed lines;

FIG. 6 is a perspective view thereof;

FIG. 7 is a right side elevation view of FIG. 6, wherein the left side elevation view is substantially a mirror image of the right side elevation view;

FIG. 8 is a top plan view of FIG. 6, wherein a bottom plan view is substantially a mirror image of the top plan view;

FIG. 9 is a front elevation view of FIG. 6; and,

FIG. 10 is a rear elevation view of FIG. 6.

The dashed lines form no part of the claimed design.
